UNITED STATES PATENT OFFICE.

HENRY W. BLOEMKER, OF PHILADELPHIA, PENNSYLVANIA, ASSIGNOR TO JOHN HANCOCK, OF PHILADELPHIA, PENNSYLVANIA,

WIRE-FABRIC MACHINE.

1,337,504.

Specification of Letters Patent. Patented Apr. 20, 1920.

Application filed October 17, 1919. Serial No. 331,277.

To all whom it may concern:

Be it known that I, HENRY W. BLOEMKER, a citizen of the United States, residing at Philadelphia, county of Philadelphia, State of Pennsylvania, have invented certain new and useful Improvements in Wire-Fabric Machines, of which the following is a specification.

Some of the objects of the present invention are to provide means for forming a wire fabric the units of which have a predetermined shape successively repeated throughout the body of the fabric; to provide means for respectively feeding a strand of wire and bending it in a predetermined manner; to provide means for successively shaping a plurality of connected units from a single strand of wire; to provide means for automatically bending and shaping a strand of wire into a substantially U form having a pair of offset loops therein; to provide means for automatically bending and shaping a strand of wire to form a plurality of units of predetermined shape in conjunction with means for arranging said units in interconnected relation in the same plane and lineally alined; and to provide other improvements as will hereinafter appear.

Referring to the drawings, Figure 1 represents a plan of one form of wire fabric forming machine embodying the present invention; Fig. 2 represents one of the complete units of the product formed by the machine; Fig. 3 represents a detail in plan of one pair of the forming jaws; Fig. 4 represents a section showing a pair of the forming jaws in side elevation; Fig. 5 represents a side elevation of the machine; Fig. 6 represents an enlarged detail in side elevation of the holding mechanism at the delivery end of the machine; Fig. 7 represents an end elevation of one form of the wire feeding mechanism; Fig. 8 represents a side elevation of the same; Fig. 9 represents a section on line 9—9 of Fig. 1; Fig. 10 represents a section on line 10—10 of Fig. 1; Fig. 11 represents a section on line 11—11 of Fig. 10; Fig. 12 represents the wire after the first forming operation; Fig. 13 represents the wire after the second operation; and Fig. 14 represents a detail in section on line 14—14 of Fig. 1.

Referring to the drawings one form of the present invention is shown in Figs. 1

and 2 wherein the operating parts of the machine are supported upon a main frame 10 of open construction having two, suitably spaced, side top bars 11 of suitable rigid material to support, accommodate 60 and conveniently provide for the moving parts.

For transmitting motion to the several mechanisms of the machine a main shaft 12 is provided which is arranged to be driven 65 from a suitable source of power, in this instance a belt driven pulley 13 fast to the shaft 12 and an idle pulley 14, while a well known type of belt shifter 15 provides for starting and stopping the machine. From 70 the shaft 12 power is transmitted by a low speed gearing 16 and 17 to a counter-shaft 18 journaled in suitable bearings 20 in the main frame 10. This counter-shaft 18 has keyed thereon a bevel gear 21 in mesh with 75 a similar gear 22 fast to an operating shaft 23 which extends lengthwise of the frame 10 and has a second bevel gear 24 keyed thereon and arranged in mesh with a bevel gear 25 fast upon a second counter-shaft 26, 80 this last being journaled in suitable bearings on the frame 10.

For guiding and feeding the wire 30 to the machine, a guide tube 31 is rigidly supported in brackets 32 and 33, respectively 85 carried by cross bars 34 and 35 which are fast to the main frame 10. The tube 31 is arranged substantially horizontal and in alinement with a suitable wire straightening device 36 of any well known form. The 90 wire 30 is fed to the tube 31 by a step by step mechanism consisting, in one form of a block 40 mounted for sliding movement upon a rod 41 and having a pair of spaced ears 42 which are suitably apertured 95 for the passage of the wire 30. Pivoted to the block 40 at opposite sides of the wire 30 are two knife edge feed fingers 43 which are arranged to have sufficient movement in order to slide freely along the wire 30 in 100 one direction of movement but to bite the wire in the other direction of movement of the block 40 and thus advance a predetermined length of the wire into the machine. Two stop pins 44 are respectively located 105 and fixed adjacent the said fingers 43 to limit the swing thereof at one side, while one of the ears 42 serves the same purpose at the opposite side. The block 40 is reciprocated intermittently by means of a le- 110

ver 45 having a pin and slot connection 46 with the block 40 and also a pivotal connection 47 intermediate of its length, with an arm 50 which is fixed to the frame 10. The 5 outer end of the lever 45 has a lost motion connection 51 with an operating rod 52 which is actuated by a moving part hereinafter to be described.

For bending and forming the wire to the 10 particular predetermined shape two sets of dies 53 and 54 are provided, the one being a duplicate of the other, said dies being respectively carried by heads 55 and 56 which are slidably mounted on two parallel 15 guide rods 57 and 58. As the operating parts of the dies 53 and 54 are similar, the description will be confined to one set. Referring to Fig. 4, the complementary die parts 53 are carried respectively by jaw members 20 60 and 61 which are pivoted respectively at 62 and 63 to the head 55 which is suitably cut away to accommodate the parts in a compact manner. At the die side of the fulcrum of the jaws a compression spring 25 64 is mounted and acts to normally hold the two die parts separated. The ends of the jaw members 60 and 61 are extended to form relatively long lever arms which when spaced or forced apart will exert sufficient 30 pressure upon the dies to shape the wire in accordance with the configuration of the dies.

For operating the jaws 60 and 61 in the required manner each pair is arranged to 35 straddle a separate cam 65, the two cams 65 being fixed to a square rock-shaft 66 which is mounted in a suitable manner for rocking movement in brackets 67 extended from and fast to the frame 10. To impart 40 rocking movement to the shaft 66 an arm 70 is fixed thereto and has pivoted connection with a link 71 which in turn is pivoted to an arm 72 suspended from and freely movable on a pivot 73 on a cross bar 74 of the frame 10. This arm 72 carries a rigid trip finger 75 located in the path of a cam roller 76 on a cam member 77 which is fixed to rotate with the shaft 23. Thus when the cam roller 76 strikes the trip finger 50 75 the rock-shaft 66 will be turned in one direction. For turning the said shaft 66 in the other direction, that is, to its initial position, a second arm 80 is suspended by a pivot 81 on the cross-bar 74 and connected 55 to the arm 72 by a link 82. This arm 80 carries a trip 84 also arranged in the path of the cam-roller 76.

As a means for reciprocating the die head 55, a connecting rod 85 is provided having 60 one end pivoted in ears 86 rigid with the head 55 and its other end connected to a crank arm 87 fast to the face of a disk 88 which is arranged to rotate with the counter-shaft 26.

65 For reciprocating the die head 56 a simi-

lar connecting rod 90 is provided having one end pivoted in ears 91 rigid with the head 56 and its other end connected to a crank arm 92 fast to the face of a disk 93 which is arranged to rotate with the counter-shaft 18.

In connection with the operation of the heads 55 and 56 it should be noted that the shafts 18 and 26 are geared to rotate at the same speed, and the operating connections are such that the two heads 55 and 56 move in synchronism, first toward each other to a predetermined position and then away from each other a predetermined distance in order that the desired forming operations 70 80 may be carried out.

For the purpose of bending the wire at substantially right angles to its path of movement through the machine to form the side legs of the fabric unit and to also form 85 a relatively long narrow loop a pusher or traveling bending rod 94 is mounted for reciprocating movement upon the frame 10 in a position to travel transversely of the path of movement of the wire and in the 90 plane thereof in order to engage the wire. Further the rod 94 is located between and substantially equidistant from the two jaw heads 53 and 54 and in meeting position of the said heads occupies the space between 95 them, there being sufficient clearance to permit free movement of the bending rod 94. The space referred to is provided by adjusting the stroke of the heads as will be 100 readily understood.

In order to reciprocate the rod 94 it is connected by a pin and slot connection 95 with a pivoted rock-arm 96 which carries a roller 97 located in the path of movement of a cam 100 fast to the shaft 23. The 105 contour of the cam 100 is such as to advance the bending rod 94 with an even, uniform motion during the bending operation but is sharply cut away to permit a quick return of the rod 94 to remove it promptly 110 so that the next wire feeding step may take place. This return movement is effected by a weight 101 suspended on a cable 102 which passes over a pulley 103 and is made fast to the rod 94 at 104.

For holding the wire and keeping it in position while under the action of the bending rod 94, a V-shaped seat 105 is formed in the end of the rod 94 to receive the wire, while at opposite sides of the shank of the 120 rod 94 are two laterally disposed fingers 106, preferably having inclined end surfaces 107 which prevent the wire from riding up out of the plane of its lateral movement.

For guiding the shaped wire while it is 125 being transferred from one die to another, and from the last die to the delivery portion of the machine, a receiving table 110 is provided leading from the delivery side of the dies 54 and having a fixed flat strip 111 se- 130

cured thereto, which has an extended and downwardly curved tongue 112 located at the receiving side of the die head 56 in such a manner that the wire meets the said tongue 5 112 and is guided thereby upwardly to a position where it can be seated in the die 54. The table 110 has a pin 113 fixed in its side walls out of the path of the wire and to which is pivoted a plate 114 provided with 10 two upwardly and inwardly turned flanges 115 and 116 for retaining the formed wire and guiding it across the delivery table 110 in a smooth and orderly manner. The flange 115, which is in close proximity to the die 15 54 is provided with a finger 117 arranged to engage the wire and cause it to be seated in the die 54 prior to the last forming step. This finger 117 also serves to prevent displacement of the wire when released from 20 die 54 and to direct it beneath the flange 115 when it is fed to the delivery table.

For raising and lowering the plate 114 with its flanges the die head 56 has fixed thereto a rigid bracket 120 provided with an 25 integral member 121 to which a tumbler 122 is pivoted in such a manner as to be positioned beneath the free end of the plate 114 and serve as a support therefor. The tumbler 122 carries a lug 123 arranged to project in the path of movement of a movable trip 124 rigid with a rod 125 having a bearing for sliding movement in the member 121. One end of the rod 125 is provided with an 30 abutment 126 arranged to be struck by the die head 55, as it advances to meet the head 56, in order to shift the rod 125 in one direction, while the other end of the rod 125 is of sufficient length to project beyond the end of the bracket 120 and engage a fixed 35 trip 127 mounted in an adjustable manner upon the rod 57. In the position of the parts shown in Fig. 6 the tumbler 122 has been lifted by the trip 124 to raise the guide plate 114 and this latter is returned to its 40 normal retaining position by means of a weight 128 which acts when the rod 125 has been shifted to remove the trip 124 from the supporting position. From the foregoing it will be apparent that while the table 45 110 is stationary it carries a pivoted flanged guide structure 114, 115 and 116 having a longitudinally disposed strip 111 which projects at the receiving end in the form of a curved tongue. The object of this construction is to allow the finished fabric to move 50 freely away from the dies without becoming bent, entangled or otherwise distorted while the successive forming operations continue. Thus when the last forming step upon one 55 of the units is completed the plate 114 is raised automatically enough to raise the wire out of the die so that the next feeding operation merely pushes the length of completed units along the plate 114 where they 60 are prevented from buckling upward by the

flanges 115 and 116. As soon as the new unit length is in place the plate 114 lowers and the finger 117 attends to placing the formed pin in the second die 54.

In Figs. 7 and 8 another form of intermittent wire feeding mechanism is shown wherein the wire 30 is directed from the straightening mechanism 36 to a guide bushing 130 fixed to a frame 131 and arranged in alignment with two superposed feed rolls 75 132 and 133, the former of which has a peripheral face of constant diameter and the latter a peripheral face of two diameters. The roll 132 is fixed to rotate with a stud shaft 134 driven by a gear 135 which is in 80 mesh with a gear 136 fast to a stud shaft 137 upon which the mutilated or intermittent feed roll 133 is fixed. The gears 135 and 136 are driven from any suitable source and rotate the two rolls at the same speed. The 85 distance between the two shafts is adjusted to bring the enlarged diameter portion 138 of the roll 133 into relatively close proximity to the peripheral face of the roll 132 so that the wire 30 is gripped and fed forward 90 into the tube 31 as will be understood.

In the operation of the machine the wire 30 leaves the straightening device 36 and is fed forward intermittently by the feed mechanism, carried by the reciprocating 95 block 40, passing through the guide tube 31 and entering the open jaws of the die 53.

The movement of the cam 77 is so timed as to rock the shaft 66 at the instant the wire 30 is seated in the die and consequently the 100 cam 65 spreads the jaw arms 60 and 61 to bring the die parts together. The result is a bending of the wire to the shape shown in Fig. 12. With this accomplished the shaft 66 rocks back, removing the cam 65 105 so that the die 53 opens, whereupon the wire 30 is again fed forward a distance sufficient to locate the formed portion in the second die 54. At the time there is a length of wire 110 extending between the two dies 53 and 54 and having its ends positioned in the respective dies. Again the shaft 66 rocks, thereby closing both dies and simultaneously the dies are advanced toward each other by the action of the connecting rods 85 and 90. In 115 this connection it should be noted that the feed operating rod 52 is attached to the head 55 and is thereby actuated to shift the feeding mechanism back to a position for the next wire feeding step.

As the two heads 55 and 56 move toward each other the cam 100 causes the bending rod 94 to move and carry the wire laterally outward between the die heads, which at the end of the stroke press the wire against 125 the sides of the rod 94 with the result that the long loop shown in Fig. 13 is formed, one leg forming a side of one unit and the other leg forming a side of the other unit. As soon as this is completed the rod 94 is 130

shot out of the way by the weight 101, the jaw arms 60 and 61, of the respective die heads 55 and 56, are released by the removal of the rock-cam 65 and the dies open. While 5 the die heads 55 and 56 are opening the guide members 115 and 116 are supported by the tumbler 122 and a new portion of the length of wire is fed forward so that when the die head 56 reaches the end of its stroke 10 the partially formed part of the new length is positioned above the die 54. At this movement the rod 125 strikes the trip 127 and is shifted to the left, as seen in Fig. 6, thereby removing the trip 124 as a support for the 15 tumbler 122 and the latter therefore drops, causing the weight 128 to lower the members 115 and 116. This results in the proper placement of the wire in the die 54 and also holds the length of formed wire in place 20 upon the delivery table 114. When the die heads 55 and 56 move forward and approach the end of the meeting stroke the abutment 126 is struck by the head 55 and shifts the rod 125 to the right, as seen in 25 Fig. 6, thereby causing the trip 124 to engage the lug 123 to raise and support the tumbler 122 in a position to hold the members 115 and 116 raised so that the wire is free to unseat and be fed forward upon the 30 succeeding feed step.

The resulting product is a succession of units, shown in Fig. 2, formed from a continuous wire and having a length determined by the size of the desired fabric, as it 35 will be evident that any number of units may make up a section and it is only necessary to cut the wire as required.

While but one form of the present invention has been illustrated and described, it 40 will be obvious that the invention is not limited to any specific construction but might be applied in various forms without departing from the spirit of the invention or the scope of the appended claims.

Having thus described my invention, I claim and desire to protect by Letters Patent of the United States:

1. A wire fabric machine comprising in combination, means for feeding a length of 50 wire intermittently, a die arranged to receive and form a portion of said wire into a predetermined shape, means for opening and closing said die in timed relation with respect to said feeding means, a second die 55 arranged to receive the shaped portion of said wire, and means to form a loop in the portion of said wire between said dies.

2. A wire fabric machine comprising in combination, means for feeding a length of 60 wire intermittently, a die arranged to receive and form a portion of said wire into a predetermined shape, means for opening and closing said die in timed relation with respect to said feeding means, a second die 65 arranged to receive the shaped portion of

said wire, means to form a loop in the portion of said wire between said dies, and means adjacent said second die for retaining and guiding said wire.

3. A wire fabric machine comprising in 70 combination, means for feeding a length of wire intermittently, a die arranged to receive and form a portion of said wire into a predetermined shape, means for opening and closing said die in timed relation with 75 respect to said feeding means, a second die, arranged to receive the shaped portion of said wire, means to form a loop in the portion of said wire between said dies, means adjacent said second die for retaining and guiding said wire, and means for raising and lowering said guiding means in timed relation to said feeding means.

4. A wire fabric machine comprising in 80 combination means for feeding a length of 85 wire intermittently, a plurality of dies arranged to successively receive and form a portion of said wire into a predetermined shape, means operative to respectively open and close said dies simultaneously at the 90 beginning and end of a feeding operation, and means arranged to operate in closed position of said dies to form a loop in the portion of said wire between said dies.

5. A wire fabric machine comprising in 95 combination means for feeding a length of wire intermittently, a plurality of dies arranged to successively receive and form a portion of said wire into a predetermined shape, means operative to respectively open 100 and close said dies simultaneously at the beginning and end of a feeding operation, means arranged to operate in closed position of said dies to form a loop in the portion of said wire between said dies, and 105 means adjacent said second die for retaining and guiding said wire.

6. A wire fabric machine comprising in combination means for feeding a length of wire intermittently, a plurality of dies arranged to successively receive and form a portion of said wire into a predetermined shape, means operative to respectively open and close said dies simultaneously at the beginning and end of a feeding operation, 110 means arranged to operate in closed position of said dies to form a loop in the portion of said wire between said dies, means adjacent said second die for retaining and guiding said wire, and means to automatically raise and lower said guiding means.

7. A wire fabric machine comprising in combination means for feeding a length of wire intermittently, a plurality of dies arranged to successively receive and form a portion of said wire into a predetermined shape, means to simultaneously close said dies after a wire feeding step to shape said wire, means to move one of said dies to 115 120 125 130

ward the other die, and means arranged to operate during the movement of said die to form a loop in the portion of the wire between said dies.

5 8. A wire fabric machine comprising in combination means for feeding a length of wire intermittently, a plurality of dies arranged to successively receive and form a portion of said wire into a predetermined 10 shape, means to simultaneously close said dies after a wire feeding step to shape said wire, means to open said dies simultaneously after a forming operation, and a bending device arranged to form a loop in 15 the portion of the wire between said dies.

9. A wire fabric machine comprising in combination, means for feeding a length of wire intermittently, means including a pair 20 of dies for successively receiving and forming a portion of said wire into a predetermined shape, and means arranged to bend the portion of said wire between said dies into a relatively long loop.

10. A wire fabric machine comprising in combination means for feeding a length of wire intermittently, means including a pair 25 of dies for successively receiving and forming a portion of said wire into a predetermined shape, means for moving said dies toward each other, and means operating 30 simultaneously with the movement of said

dies and transversely to the direction of movement thereof for bending the portion of wire between said dies into a relatively long loop.

35

11. A wire fabric machine comprising in combination means for feeding a length of wire intermittently, means including a pair of dies for successively receiving and forming a portion of said wire into a predetermined 40 shape; means for moving said dies toward each other, means operating simultaneously with the movement of said dies and transversely to the direction of movement thereof for bending the portion of 45 wire between said dies into a relatively long loop, and a quick return mechanism for shifting said bending means out of operative engagement with said wire.

12. A wire fabric machine comprising in combination means for feeding a length of wire intermittently, means for bending said wire to a predetermined shape, a receiving table at the delivery end of said machine, a pivoted device for guiding the 50 formed wire to said table, and means for raising and lowering said device in timed relation to the movement of said wire.

In witness whereof I have hereunto set my hand this 15th day of October, 1919. 60

HENRY W. BLOEMKER.
